E. T. LEE
ROLLER SKATE

APPLICATION FILED JAN. 7, 1920.

1,346,218.

Patented July 13, 1920.

UNITED STATES PATENT OFFICE.

ELMER T. LEE, OF WATERBURY, CONNECTICUT.

ROLLER-SKATE.

1,346,218.

Specification of Letters Patent. Patented July 13, 1920.

Application filed January 7, 1920. Serial No. 349,924.

To all whom it may concern:

Be it known that I, ELMER T. LEE, a citizen of the United States, and a resident of Waterbury, in the county of New Haven and 5 State of Connecticut, have invented certain new and useful Improvements in Roller-Skates, which improvements are fully set forth in the following specification.

This invention relates to improvements in 10 skates, and more particularly skates of the so-called roller type; and its object is to provide a roller skate which shall be simple and inexpensive as regards its construction; durable, efficient and reliable in practical 15 service; convenient in its application to practical purposes; and which shall possess certain well-defined advantages over prior analogous constructions.

The invention consists in certain combinations, details and parts whereby, together 20 with the novel disposition and relative arrangement of said parts, the attainment of the foregoing object is rendered practicable, all of which will be hereinafter more specifically referred to and set forth in the 25 claims hereto appended.

The invention is clearly illustrated in the accompanying drawing, wherein:

Figure 1 is a diagrammatic view of a 30 sheet-metal blank usable in the formation of the heel-section of the supporting body of my improved skate.

Fig. 2 is a top plan view of a roller skate embodying my said improvements.

Fig. 3 is a side elevation thereof.

Fig. 4 is a central-vertical longitudinal section of same, as along the dotted line 4—4 of Fig. 2, the bearing-rollers removed.

Fig. 5 is a vertical transverse section, as 40 along the dotted line 5—5 of Fig. 3.

Fig. 6 is a rear end view of the skate.

Having reference to the accompanying drawing, wherein similar reference-numerals denote like parts throughout the several views, I, in carrying out my present invention, make use of a supporting body consisting of a heel-plate 6 and a sole-plate 7, said heel-plate and sole-plate being so adjustably conjoined, each with the other, as to 50 be longitudinally extensible, each relatively to the other.

The heel-plate 6 is best stamped from metal in sheet-form and in its primarily blanked form, as shown approximately in 55 Fig. 1, is approximately flat and has opposite, lateral flaps 6', 6'', which are turned,

each downwardly and returned beneath the advance or "instep" segment of said heel-plate, in spaced parallel relation therewith, said flaps being terminated, each materially 60 short of the other, whereby an unoccupied, slot-like space 6''' is left between them, and forming between them opposite guide-ways 7' 7'' into which projects endwise and slidingly operates the flat, relatively narrowed 65 shank 8 of the sole-plate 7.

The heel-plate 6 is provided with a medial longitudinal slot 8', open at its advance end, and which lies in registry with the open space 6''' thereunder. 70

8'' denotes a screw-bolt projecting downwardly through the assembled heel-plate segment and sole-plate shank, by way of the slot 8' of the former and a suitable opening 9 formed in the latter, said screw-bolt having a relatively enlarged head overlying the heel-plate segment at opposite sides of the slot 8', and having a suitable nut, 9', preferably of the finger type, threaded thereon at its lower end-portion, occupying the space 80 6''', and securely locking between itself and the head aforesaid, when turned duly homeward, the heel-plate segment and sole-plate shank assembled as stated. 75

It will be understood that these parts may 85 be released for longitudinal adjustment, each relatively to the other, by reversely turning the nut 9', and whenever it may be desired to lengthen or shorten the skate; and it will be further understood that deflection of 90 either the sole-plate or heel-plate relatively to the other, is exceptionally well overcome, by reason of the extended bearing which the shank of the sole-plate has at all points with- 95 in the guide-ways wherein it operates.

There are firmly attached, as by means of rivets 9'', 9''', and 10, 10', respectively, to the sole-plate 7 and depending therefrom, opposite sheet-metal hangers 10'', 10''', the one turned midway thereof and suitably 100 upon itself to form therefor an axle-sleeve 11, and the other correspondingly turned to form therefor a like axle-sleeve 11', said sleeves 11, 11', standing in axial alinement each with the other, and wherein is positioned, firmly as through the medium of retaining-pins 11'', 11''', a front axle 12, on which is mounted to rotate a bearing-roller 12', there being also attached, as by means of rivets 12'', 12''', to the heel-plate 6, and 110 depending therefrom a hanger 13, conforming in all essential details to either of the

hangers 10", 10'", and hence fitted at its lower extremity with an axle-sleeve 13', corresponding to either of the axle-sleeves 11, 11', wherein is positioned, firmly as through 5 the medium of a retaining-pin 13", a rear axle 14, on which are mounted to rotate, at the opposite sides of the hanger 13, opposite bearing-rollers 14', 14", each of the several 10 bearing-rollers made use of having its periphery contracted width-wise relatively to the hub or central portion thereof, substantially as shown in Figs. 5 and 6.

The several hangers made use of are rendered serviceably rigid, respectively, by 15 means of intermediate braces 15, 15', 15", one for each hanger.

There is further firmly attached to the sole-plate 7, as through the medium of rivets 16, 16', and depending therefrom, in advance 20 of the hangers 10", 10'", a minor hanger 16", wherein is positioned, firmly as through the medium of a suitable bolt-retaining pin 17, an operating-bolt 17', having toe-clamps 17", 17'", loosely disposed thereon at the opposite 25 sides of the sole-plate 7, and threaded at its opposite ends to receive adjusting nuts 18, 18', whereby said clamps are drawn, each toward the other, for a locking engagement with the sole of the foot-covering worn by 30 the user, or released from such locking engagement, accordingly as said nuts, or either thereof, shall be directly or reversely turned on said operating-bolt, said clamps being provided with relatively extended shanks 35 jointly pierced by said operating-bolt, substantially as shown.

The heel-clip 8"" is provided with suitable, opposite openings 18", 18'", to facilitate the use of an ankle strap, as in common 40 practice.

The manner of applying my improved skate to the foot-covering of the wearer, will be apparent from the foregoing description thereof; and it will be seen that the 45 skate is not only well adapted for the purposes for which it is intended, being simple and cheap to produce and insuring, by reason of the peripherally contracted bearing-rollers made use of, surface-contact ad-

vantages not present in prior analogous devices, but may be modified to a considerable extent, particularly as regards the details of construction thereof, without materially departing from the spirit and principle of my invention as set forth and coming within 55 the scope of, the claims hereto appended.

I claim:

1. A roller skate comprising a supporting body consisting of a relatively flat heel-plate having guide-ways at the opposite 60 sides of the advance portion thereof; a sole-plate having a relatively flat shank fitting and adjustably secured within said guide-ways; sheet-metal hangers depending, a pair thereof duly spaced from said sole-plate and 65 one thereof from said heel-plate; an axle fixed in said pair of hangers and having a bearing-roller rotatable thereon between said pair of hangers; an axle fixed in the hanger depending from said heel-plate and having 70 a pair of bearing-rollers rotatable thereon, at the opposite sides of the hanger supporting the same; and means for attaching said skate to the foot-covering of the user, each of said hangers affording an axle-sleeve for 75 the reception of the axle provided for co-operation therewith.

2. A roller skate comprising a supporting body consisting of a relatively flat heel-plate having guide-ways at the opposite 80 sides of the advance portion thereof; a sole-plate having a relatively flat shank fitting and adjustably secured within said guide-ways; sheet-metal hangers depending, a pair thereof duly spaced from said sole-plate and one thereof from said heel-plate; an axle fixed in said pair of hangers and having a bearing-roller rotatable thereon between said pair of hangers; an axle fixed 85 in the hanger depending from said heel-plate and having a pair of bearing-rollers rotatable thereon, at the opposite sides of the hanger supporting the same; and means for attaching said skate to the foot-covering of the user, each of said bearing-rollers having 90 its periphery contracted widthwise relatively to the hub or central portion thereof.

ELMER T. LEE.
